UNITED STATES PATENT OFFICE.

CHARLES M. WICKHAM, OF ROCKFORD, ILLINOIS.

SPIKE.

1,092,683.

Specification of Letters Patent.

Patented Apr. 7, 1914.

Application filed September 6, 1911. Serial No. 647,859.

To all whom it may concern:

Be it known that I, CHARLES M. WICKHAM, a citizen of the United States, residing at Rockford, in the county of Winnebago and State of Illinois, have invented new and useful Improvements in Spikes, of which the following is a specification.

The invention relates more particularly to spikes for securing railroad rails to wooden cross ties, and its general object is to prevent the accidental pulling out or the working loose of the spikes by the jars and strains on the rails and this, without increasing the cost of manufacture or the weights of the spikes.

Other objects will appear and be better understood from the following description taken in connection with the accompanying drawings, in which,

20 Figure 1 is a front elevation of the spike. Fig. 2 is a side view thereof. Fig. 3 is a view similar to Fig. 1 of a modified form of spike.

In the embodiment shown in Figs. 1 and 25 5 indicates the shank, the front and rear faces of which converge at one end so as to provide the point or sharpened edge 6, and 7 indicates the head at the opposite end of the shank. 8 indicates a portion of the head 30 which overhangs the front face of the spike so as to engage the rail flange in the ordinary manner. 9 indicates a series of transverse notches in one side face of the shank and 10 a similar series in the opposite side 35 face and preferably formed in alternate arrangement with the notches 10. The floor 11 of each notch constitutes a shoulder and is perfectly flat and extends through the side front and rear faces in a plane at right 40 angles to the long axis of the shank, whereas the side wall 12 of each notch inclines downwardly and inwardly to the inner ends of said shoulders. Each shoulder of one 45 side being located centrally between a pair of shoulders on the opposite side faces.

From the foregoing it will have been observed that the planes of the several shoul-

ders are at right angles to the horizontal plane of the sharpened edge or point 6. When it is remembered that the sharpened 50 edge enters the wood crosswise of the grain thereof and the fibers are compressed laterally to admit the entering of the spike, it will be manifest that when the spike is driven home the fibers of the wood as they 55 tend to assume their normal positions will enter the notches 9 and bear upon the shoulders 10, whereby, to interlock the spike with the tie and prevent the withdrawal thereof by the ordinary strains to which the rails 60 are subjected.

In the form shown in Fig. 3, the shoulders 14 increase in width progressively from the upper to the lower notches 15 in each series. In support of this structure it may 65 be stated that when the spike is in the cross tie and the fibers, by their tendency to approach each other, have arranged themselves in the notches 15, the fibers in the upper portion of the tie or adjacent to the upper 70 surface thereof will be under greater tension than those in the notches farther down on the spike for the reason that the upper notches are, owing to the narrowness of the upper shoulders, more shallow than the 75 lower notches. This will have the effect of producing a tighter grip on the upper end portion of the spike than on the lower, whereby, the tendency of the spike to wobble under the lateral stresses produced on 80 the head by creeping or springing of the rails will, in a great measure, be overcome and at the same time the upper end portion of the spike will be strengthened over and above that it would be if the upper notches 85 were of the same depth as the lower, whereby, to prevent bending of the upper end portion as the spike is being driven into the tie.

Although I have shown and described one 90 embodiment of the invention it is to be understood that I am not to be limited to the specific arrangement and construction of parts since various changes will be made,

within the scope of the appended claim without departing from the spirit or sacrificing any of the advantages of the invention.

What I claim as new is:

- 5 A spike comprising a shank having its opposite side faces provided with a plurality of notches forming horizontally disposed shoulders arranged in staggered relations, the terminals of said shoulders lying in a
- 10 plane with said side faces, and said shoul-

ders increasing in width successively from the upper to the lower end to effect a tight grip on the upper part of the spike for the purpose set forth.

In testimony whereof I affix my signature in presence of two witnesses.

CHARLES M. WICKHAM.
